Primary Examiner — Rebekah A Caruso

(57) **CLAIM**

The ornamental design for a tripod phone case, as shown and described.

DESCRIPTION

FIG. 1 is a front view of a tripod phone case showing my new design;

FIG. 2 is a rear view of the tripod phone case;

FIG. 3 is a right side view of the tripod phone case;

FIG. 4 is a left side view of the tripod phone case;

FIG. 5 is a top view of the tripod phone case;

FIG. 6 is a bottom view of the tripod phone case; and,

FIG. 7 is a top front side perspective view of the tripod phone case in an alternative position.

The portions of the article shown in broken lines form no part of the claimed design.
